United States Patent Office

Des. 216,724
Patented Mar. 3, 1970

216,724

TOY DESK OR SIMILAR ARTICLE

Alan Sherman, Maryland Heights, Mo., assignor to Turco Manufacturing Company, DuQuoin, Ill., a corporation of Missouri

Filed Dec. 6, 1968, Ser. No. 14,833

Term of patent 14 years

Int. Cl. D6—01

U.S. Cl. D34—15

FIG. 1 is a top perspective view of a toy desk embodying my new design;

FIG. 2 is a rear elevational view thereof;

FIG. 3 is a top plan view thereof;

FIG. 4 is a front elevational view thereof; and

FIG. 5 is a side elevational view thereof.

I claim:

The ornamental design for a toy desk or similar article, substantially as shown.
